By Attorney

UNITED STATES PATENT OFFICE.

JEAN MIGNOLET, OF DENVER, COLORADO.

DESIGN FOR AN INTERNATIONAL PATRIOTIC EMBLEM.

52,337.

Specification for Design.

Patented Aug. 27, 1918.

Application filed November 30, 1917. Serial No. 204,772. Term of patent 7 years.

To all whom it may concern:

Be it known that I, JEAN MIGNOLET, a subject of the King of Belgium, residing at the city and county of Denver and State of Colorado, have invented a new, original, and ornamental Design for an International Patriotic Emblem, of which the following is a specification, reference being had to the accompanying drawing, forming a part thereof.

The figure is a front view of an international patriotic emblem showing my new design.

I claim:

The ornamental design for an international patriotic emblem as shown.

In testimony whereof I affix my signature.

JEAN MIGNOLET.
